NORRIS ELMORE CLARK, OF PLAINVILLE, CONNECTICUT.

SLITTING MECHANISM.

No. 930,349.

Specification of Letters Patent.

Patented Aug. 10, 1909.

Application filed November 13, 1907. Serial No. 401,934.

To all whom it may concern:

Be it known that I, NORRIS ELMORE CLARK, a citizen of the United States, residing at Plainville, in the county of Hartford and State of Connecticut, have invented certain new and useful Improvements in Slitting Mechanism, of which the following is a specification.

My invention relates to mechanism for slitting or lancing sheets or plates, particularly of metal.

The main object is to provide simple and reliable mechanism for forming relatively staggered slits in sheet metal, and leaving it substantially flat so that the product may be subsequently stretched or expanded by suitable mechanism. I have also sought to perfect the details of construction whereby the cutters may be readily manufactured, installed, adjusted, removed and kept in working condition.

Another object is to prevent yielding of the cutters when in operation and any consequent irregularity in the product.

The mechanism is adapted to be installed and used in a suitable reciprocating press with suitable feed rolls or other devices such as are in common use.

The accompanying two sheets of drawings illustrate details of one form of the invention.

Figure 1. is a view of the under side of the punch member, part being shown in section. Fig. 2. is a plan view of the die member, part being shown in section. Fig. 3. is a detail view showing a fragment of the product of the mechanism. Fig. 4. is a cross sectional view of the entire mechanism on the plane of the line XX of Figs. 1 and 2. Figs. 5. and 3. are side and sectional views respectively of a cutter such as is used in the die set and in the front row of the punch set. Figs. 7. and 8. are side and sectional views respectively of a cutter such as is used in the back row of the punch set. Fig. 9. is a front view of the back rows of cutters showing two of the through bolts in section. Fig. 10. is a front view of the front rows of cutters showing the securing bolts and through bolts in section.

The punch-holder 1 is secured in suitable manner to the reciprocating gate or head 2, while the die holder 3 is secured to the stationary bed or frame 4. The stock 5, for instance, sheet steel, is fed intermittently over a table 6, and transverse rows of slits such as

7 and 8 are formed by the cutters, the slits in one row being staggered laterally with relation to the slits in the adjacent rows. All the slits in row 7 are formed by the front rows of cutters at the same time that the slits in row 8 are formed by the back rows of cutters. As the stock is fed along step by step in the direction of the arrows in Figs. 3 and 4, all the succeeding slits in column 9 are formed by the same upper and lower pair of back cutters, and all the slits in column 10 are formed by a single pair of upper and lower front cutters as will be more fully understood from the following detail description. The feed after each stroke is equal to the distance between slits of a column and the distance between the cutting edges of the front and back cutters is equal to two and a half times the feed.

The holders 1 and 3 are formed from solid castings with transverse grooves for receiving the cutters. These grooves have parallel sides 11, 12, 13, 14, and the cutters are perfectly flat so that the alinement is perfect.

All the die cutters 15, 15, and 16, 16, are like cutter 15, shown in Figs. 5 and 6 except that some of them are centrally perforated as will be hereafter understood. The cutting edge 17, is straight and equal to the length of the slit desired. The face of the cutter is beveled as shown at 18 Fig. 6, so as to facilitate a shearing cut. The ends of the cutters abut against one another so that the position of each cutter is readily determined. Each corner of the cutting face is beveled as 19 so as to prevent cutting the bonds. A recess 20 is formed in each end to allow for the clamp bolts 21, 21. The nut 22 for each clamp bolt is inside the groove of the holder and operates against the two adjacent cutters so that each cutter is clamped securely on both ends. The cutters 16, 16, are secured in the same manner by bolts such as 23, 23, and nuts 24, 24. Some of these bolts, such as 25, pass through the holder and the front cutters 15, and are provided with intermediate nuts such as 26 and exterior nuts such as 27, so as to tie the holder together and prevent the parts from springing. A bar 28 spaces the rows of the die cutters and serves to protect the nuts between the rows.

All the cutters 30, 30, of the front row of punch cutters are like die cutter 15, and are held in place by bolts 31, 31, in the same manner as the die cutters.

12
All the cutters 32, 32, of the back row of punch cutters are like the cutter shown in Figs. 7 and 8 except for the perforation 33, which is only provided in the back cutters where the through bolts 34, 34, pass. The others are simply held in place by the bolts 35, 35, which pass between the ends of the adjacent cutters and have clamp nuts 36, 36. The through bolts 34, 34, have interior nuts 37, 37, and exterior nuts 38, 38. A space bar 39 is located between the front and back punch cutters. The corners of each back punch cutter are beveled as at 40 and the face beveled as at 41 similar to the other cutters, but the cutting edge has a short, straight portion 42, and is sloped off or crowned as at 43, 43. These back punch cutters 32, 32, in conjunction with the back die cutters 16, 16, act upon the solid stock, and I have found that the shape of the cutting faces and edges produces a clean cut without injury to the stock and without material bending of the strands.

25 After the back cutters have formed rows of slits as shown at the lower edge of Fig. 3, the stock comes under the action of the front punch cutters 30, 30, and die cutters 15, 15, which split the ends of the strands formed by the back cutters and thus form the desired substantially flat product with relatively staggered slits as shown in the upper part of Fig. 3.

35 Although the operation of this mechanism in its preferred form does not remove any stock, I have used the term "punch" member simply to render reference to the location and general relative movement more easy. It is obvious that the upper member might be stationary and the lower member mov-

40 able.

What I claim is:

1. Slitting mechanism comprising spaced rows of punch and die cutters arranged in staggered relation, the cutters in each row abutting against each other at the ends and being beveled on the corners and beveled on the faces away from the cutting edges.

50 2. Slitting mechanism comprising spaced rows of punch and die cutters arranged in staggered relation, the cutters in each row abutting against each other at the ends and being beveled on the corners and beveled on the faces away from the cutting edges, the cutting edges of the back punch cutters being 55 also crowned or sloped toward the corners.

3. Slitting mechanism comprising double rows of flat punch and die cutters arranged in staggered relation, the cutting edges of the front punch cutters and of all the die cutters 60 being straight across and the cutting edge of each back punch cutter sloping toward the ends.

4. Slitting mechanism comprising two rows of punch cutters and two rows of die cutters all arranged in transversely staggered

relation, the cutting edge of each cutter in all four rows being straight, across at least its central portion.

5. Slitting mechanism comprising two rows of punch cutters and two rows of die cutters all arranged in transversely staggered relation, the cutting edge of each cutter in all four rows being straight, across at least its central portion, the cutting edge of each cutter in one of the back rows being also sloped 75 away from the straight central portion toward the ends.

6. Slitting mechanism comprising spaced rows of punch and die cutters in transversely staggered relation each cutter in all the rows 80 being beveled on the corners and having a cutting face with an edge straight across a portion of it.

7. In slitting mechanism a rigid holder having a transverse groove, two rows of flat 85 cutters arranged in said groove in staggered relation, a space bar between the rows and means for holding the cutters in place.

8. Slitting mechanism including a holder having a groove with straight parallel walls, 90 two rows of flat cutters arranged in staggered relation in said groove, each cutter abutting against the ends of the adjacent cutters and being beveled on the corners and straight across a portion.

9. Slitting mechanism including a holder having a transverse groove with straight parallel walls, two rows of staggered flat cutters and means for clamping each cutter in place against one wall, the ends of the cutters abut- 100 ting against each other.

10. Slitting mechanism including a holder having a groove, two rows of cutters in said groove and abutting against each other, means for clamping the cutter in one row to 105 one wall of the groove and means for clamping the cutters in the other row to the opposite wall of the groove.

11. Slitting mechanism including a holder having a groove, two rows of cutters in said groove and abutting against each other, means for clamping the cutters in one row to one wall of the groove, and means for clamping the cutters in the other row to the opposite wall of the groove, and means for clamping the two walls of the holder toward each other.

12. Slitting mechanism including a holder, a row of cutters abutting against each other and beveled on their corners, each cutter having an open recess at its end and bolts passing through said recesses and clamping the cutters in the holder.

13. Slitting mechanism including a holder, a row of cutters and clamp bolts passing between the ends of adjacent cutters and each holding two cutters in place.

14. Slitting mechanism including a grooved holder, two spaced rows of cutters in staggered relation in the groove, clamp bolts 130

passing between the ends of adjacent cutters and clamp nuts on the bolts between the rows of cutters.

15. Slitting mechanism including a grooved holder, two spaced rows of cutters in staggered relation in said groove, clamp bolts passing between the adjacent cutters of one row, and other clamp bolts passing between the adjacent cutters of the other row.
- 10 16. Slitting mechanism including a grooved holder, two spaced rows of cutters in staggered relation in said groove, clamp bolts passing between the adjacent cutters of one row, and other clamp bolts passing between the adjacent cutters of the other row, some of said bolts extending through the cutters which are opposite the interval of the cutters between which they pass.
17. Slitting mechanism comprising upper and lower holders each having two transversely extending parallel walls, a row of flat abutting cutters alined with each wall and having beveled corners, the cutters of one upper row registering with the cutters of one lower row, means for securing said upper row to one of said walls, the cutters of the other upper row registering with the cutters of the other lower row and staggered with relation to the first mentioned rows and means for securing the cutters of the second mentioned lower row with their cutting faces against one of the lower walls.
18. Slitting mechanism comprising upper and lower holders, each having parallel walls, two rows of cutters for each holder, the cutters of each row being flat and abutting on the ends, the cutters of one upper and one lower row forming a set registering with each other and being staggered with relation to the registering cutters of the other set, the cutting sides of the cutters of one upper row

and the cutting sides of the relatively staggered lower row bearing against opposite walls of the upper and lower holders.

19. Slitting mechanism including upper and lower holders each having a flat continuous vertical wall, and two sets of flat cutters in staggered relation in each holder, the cutting sides of the cutters in one row of each set being held to and bearing against the wall of its holder.

20. Slitting mechanism including upper and lower holders each having a flat continuous vertical wall and two sets of flat cutters in staggered relation in each holder, the cutting sides of the cutters in one row of each set being held to and bearing against the wall of its holder, and flat continuous vertical bearing walls for the opposite sides of the other cutters of each holder.

21. Slitting mechanism comprising upper and lower sets of transversely extending staggered cutters having beveled cutting faces and holders for said sets supporting each cutter throughout substantially its entire height from the back ends to the base of the bevel.

22. In sheet metal slitting mechanism, a holder having a transverse groove with parallel opposite walls, two rows of cutters arranged in said groove in staggered relation and means for rigidly securing said cutters in parallel alinement with the opposite walls of said groove, the cutting edges projecting beyond the groove a distance substantially equal to the thickness of stock to be slitted.

In testimony whereof I affix my signature in presence of two witnesses.
